UNITED STATES PATENT OFFICE.

JOHN G. LYON, OF PITTSBURG, PENNSYLVANIA.

DESIGN FOR AN INKSTAND-COVER.

SPECIFICATION forming part of Design No. 20,046, dated July 22, 1890.

Application filed March 26, 1890. Serial No. 345,457. Term of patent 14 years.

To all whom it may concern:

Be it known that I, JOHN G. LYON, a resident of Pittsburg, in the county of Allegheny and State of Pennsylvania, have invented a new and original Design for Inkstands; and I do hereby declare the following to be a full, clear, and exact description thereof, reference being had to the accompanying drawings, in which—

10 Figure 1 is a side view of the cover, showing the inkstand in dotted lines. Fig. 2 is a face view showing the cover raised slightly and showing the inkstand in dotted lines, and Fig. 3 is a top view of the cover.

15 Like letters of reference indicate like parts in each.

My design relates to inkstand-covers; and it consists, essentially, in an enlarged bulbous or globous body extending out beyond the 20 base and having spiral corrugations thereon.

In the drawings, the body a of the inkstand is shown in dotted lines, it having the collar a' at the neck, to which is hinged the circular base b of the cover, which has a ring b', 25 the base b being generally smooth. The body of the cover is formed of a bulb or globe c, secured to the base b and extending above the same, this bulbous or globous body being of greater diameter than the base b and extending out beyond the same, as shown. On 30 the surface of this bulbous or globous body are the spiral corrugations or ribs d, which are shown as convex in shape, and which in the glass body impart a handsome appearance to the cover, the spiral corrugations on 35 one side of the body giving a series of ever-changing lines when seen through the opposite side of the glass body. At the same time the large globous top or cover imparts a massive effect to the inkstand. 40

What I claim as my design is—

The design for inkstand-cover herein shown and described.

In testimony whereof I, the said JOHN G. LYON, have hereunto set my hand.

JNO. G. LYON.
